UNITED STATES PATENT OFFICE.

JAMES ALBERT COREY, OF DATCHET, ENGLAND.

ELECTRODEPOSITION OF METALS.

1,036,571.

Specification of Letters Patent. Patented Aug. 27, 1912.

Application filed January 13, 1911. Serial No. 602,455.

To all whom it may concern:

Be it known that I, JAMES ALBERT COREY, a subject of the King of Great Britain and Ireland, residing at "Ontario," Montague 5 Road, Datchet, England, have invented certain new and useful Improvements in and Relating to the Electrodeposition of Metals, of which the following is a specification.

This invention relates to apparatus for 10 electro-depositing metals and more particularly to apparatus for the production of printers' electrotypes for use with high current densities of the kind in which there is mounted within a circular vat an annular 15 negative electrode which is rotated for the movement of the cathode in the electrolyte, and the invention has for its object to provide an apparatus of improved construction adapted to work economically with high 20 current densities and whose operation is simple, convenient and effective; and the invention comprises an improved construction and arrangement of the cathode and 25 anode carriers and means for passing current therethrough, and for rotating the cathode; also an improved mold or plate 30 holder by which good contact with the cathode carrier is always insured; and improved means for filtering and maintaining constant the strength of the electrolyte without the necessity of interrupting the working of the apparatus.

According to the invention the negative electrode carrier is provided as a ring carried 35 by suitable arms from a vertical spindle mounted so as to rotate upon ball bearings and adapted to be driven by any suitable form of driving gear. The electrode ring is advantageously of a substantially 40 rectangular cross-section the upper surface of which is formed as a ridge or with ridges having two inclined faces to form contact 45 surfaces for the reception of the plate or mold holders which are formed with correspondingly shaped contact surfaces.

The positive electrode carrier is provided 50 as a stationary ring carried by arms or other suitable means from a pedestal or the like and is preferably formed with contact surfaces for the reception of the anode plate 55 holders, similar to those on the negative electrode.

According to the invention, moreover, means are provided for filtering the electrolyte and maintaining the strength thereof at a constant value without necessitating

any interruption of the working of the apparatus, the electrolyte being withdrawn from the vat and led to the filter and to the means employed for maintaining the strength, by an air injecting device adapted to force air into an outlet pipe so as to produce suction therein by which the electrolyte is drawn from the vat.

In order that the speed of rotation of the negative electrode may be under control according to the invention a variable speed driving gear may be provided of any suitable type. The preferred form of gear, however, consists of a friction disk or plate 70 secured to the upper extremity of the spindle supporting the negative electrode and a driving friction wheel slidably mounted upon a transversely disposed driving shaft and adapted to contact with the face of the friction disk and to be moved to any desired distance from the center of the disk according to the speed it is desired to give to the electrode.

The invention also covers the constructional details hereinafter more fully described.

It is found that by the use of the apparatus according to the invention it is possible to increase the working voltage and thereby 85 to secure a proportional increase of current without an appreciable increase of resistance, in the electrolyte, the ratio between the values of the voltage and the current being 90 approximately constant for all voltages which are used in practical work. As the result of this feature in the working of the apparatus, high current densities can be used in an economical manner and the output of such apparatus thereby materially increased.

The invention is illustrated, by way of example, in the accompanying drawings in which—

Figure 1 is a sectional elevation of the apparatus provided according to the invention. Fig. 2 is a plan of the variable speed gear. Figs. 3 and 4 are respectively side and front elevations on an enlarged scale of the mold or plate holders or carriers.

In carrying the invention into effect according to the construction illustrated in the drawing, a circular lead-lined vat a is provided in which the electrolyte is contained and above the vat there is provided a frame a^1 carrying the bearing a^2 and the driving gear for the spindle a^3 . Provision is made

at the upper end of the bearing a^2 for the mounting of one member of a ball bearing a^3 by which the weight of the spindle and electrode carrier are taken, and upon either side of the bearing on the frame a^1 there are provided upstanding arms a^4 having bearings for the reception of the driving shaft d of the driving gear.

The spindle c^1 is provided as a hollow shaft disposed in the bearing a^2 and having secured to its upper extremity the friction disk d^1 or other driven member of the driving gear by means of a set screw and a collar d^2 screwed upon the shaft and preferably recessed into the friction disk. At the lower end of the boss of the friction disk there is mounted the second member of the race for the ball bearing a^3 which member is advantageously provided with a downwardly projecting dust-excluding flange. At the lower extremity of the spindle c^1 there is mounted a fitting c^2 held in place thereon by a set screw and a collar c^3 upon which fitting are secured a number of downwardly and outwardly projecting arms c^4 to the outer extremities of which the ring carrier c for the negative electrode is secured.

In the center of the vat there is disposed a cylindrical earthenware or the like pedestal e the upper extremity of which extends above the level of the electrolyte and is closed by a plate e^1 which is provided with a number of outwardly projecting arms e^2 to the outer extremities of which the ring carrier b for the positive electrode is secured. The plate e^1 is provided at the center with an upwardly extending boss e^3 which serves as a seat for a tube or the like e^4 extending through the hollow spindle c^1 and may be adapted to serve as a conduit for the positive cables or leads b^1 which are led therein at the upper extremity and are brought out through slots or holes near the lower extremity of the tube, which is secured to the boss or seat e^4 and connected to the ring carrier b for the positive electrode by any suitable means. Near the lower extremity of the spindle c^1 there is mounted upon the tube e^4 but insulated from it, a slip ring c^5 secured in position by an insulated screw or the like, and at the lower end of the slip ring there are provided sockets in a fitting c^6 in contact with the slip ring to receive the ends of the negative cables or leads c^7 which are led away through an aperture in the cover plate e^1 , through the pedestal e . The current is led from the negative electrode c to the slip ring c^5 by means of a set of brushes of any suitable kind. Each set of brushes is conveniently carried on a vertically disposed spindle f carried at one extremity by a lug f^1 provided for the purpose at the inner end of the arm c^4 and at the other extremity by a stay f^2 secured to the outer end of the arm c^4 . The brush holders

may be of any usual form or a holder may be provided comprising an arm carried on the spindle f and having at its projecting end a socket for the reception of the brush which is pressed into contact with the slip ring c^5 by means of a pivoted spring-actuated finger, the tension of the spring being capable of regulation.

The ring-electrode carriers b c are formed at intervals with short wedge-shaped or beveled ridges p upon their upper surfaces or edges upon which the mold or cathode plate holders g and the anode plate holders are provided to be received.

The mold or plate holders or carriers g (Figs. 3 and 4) are formed with a hook-like portion g^1 slightly displaced to one side of the flat metal body of the holder and provided with a V shaped opening on the underside, adjacent the body of the holder, the inclined faces g^2 of which opening are recessed or cut away at the middle of their length so as to leave at each end of the opening a pair of oppositely disposed and raised inclined faces. By such a construction the said faces can be readily cleaned without danger of rounding them or destroying their true alignment. At a position substantially near the lower edge of the ring electrode-carrier when the holder g is suspended thereon the adjacent face of the body part of the holder is provided with a pair of raised contact faces g^4 adapted to contact against the ring electrode-carrier and immediately below a hole is formed through the body of the plate holder in which is loosely mounted a specially formed clamping bolt r . The said bolt is of an L shape and has one of its limbs which passes through the holder screw-threaded for the greater portion of its length to receive a locking nut r^3 and is provided with a cam surface or eccentrically disposed projecting part r^4 for the purpose hereinafter described. The second limb is provided with a flattened face r^2 on the inner side.

The holder g is attached to the ring electrode-carrier by hanging it upon one of the wedge-shaped ridges and rotating the clamping bolt to bring the cam surface thereof with pressure against the lower surface of the ring electrode-carrier thus drawing the inclined faces g^2 of the portion g^1 into good electrical contact with the wedge-shaped ridge. Upon screwing home the locking nut r^3 the flat face r^2 of the second limb of the bolt is brought with pressure against the inside of the ring electrode-carrier to draw the contact faces g^4 of the holder g into good electrical contact with the ring electrode-carrier. Near the lower extremity of the holder there is provided a hole g^3 for the reception of a bolt or pin by which the mold or cathode plate is clamped or fastened to the holder. If it is desired, a

handle-like extension g^5 may be provided at the upper end of the holder. The surfaces so provided on the holder for contact with the electrodes and molds or plates are readily cleaned and kept in an efficient working condition. If the clamping bolt is not used the electrode ring c may be grooved vertically below each of the ridges p to receive the points of screws, pins or the like mounted in the holders g and adapted to engage the grooves when the holders are in position on the electrode carriers to prevent the holders from swinging upon the rotation of the electrode. The positive electrode carrier is advantageously of similar construction to that of the negative electrode carrier in which case the anode plate holders are similar to the holders g but are bolted or sweated to the plates and provided to be clamped freely in position upon the electrode-carrier.

In order that the temperature of the electrolyte may be varied or controlled as may be desired according to the requirements of the work, there is provided upon the floor of the vat a , as shown in the drawing, or around the interior, a coiled pipe h provided with an inlet pipe and an outlet pipe, through which steam or water may be circulated for the purpose of heating or cooling the electrolyte so as to secure the desired temperature. The supplies of steam and water may be led into the inlet pipe h^1 by means of a three-way valve of any suitable kind.

For the purpose of providing for the filtration of the electrolyte and for maintaining constant the strength thereof during the working of the apparatus, there is provided an air supply pipe j leading into the vat and having an upwardly directed extremity furnished with a nozzle j^1 the orifice of which is disposed within the flared or bell-shaped mouth k^1 of a pipe k leading to a suitable filtering and concentrating apparatus. The air supply pipe is connected with any source of compressed air, but preferably with an air pump driven by any suitable means by which air is forced under considerable pressure from the nozzle j^1 into the pipe k thus drawing or sucking the electrolyte into the pipe k and to an apparatus where it is filtered and the deficiency in the strength of the solution made up and whence it is returned to the vat a by a pipe l . The air nozzle j^1 and the mouth k^1 of the pipe k are preferably inclosed within a perforated cage m . It is desirable that means should be provided for regulating the temperature of the electrolyte in the filtration apparatus or in the tank.

The driving gear, illustrated in Figs. 1 and 2, comprises a driving shaft d carried in the bearings in the arms a^4 and provided at one extremity with two loose pulleys d^4 and a fast pulley d^5 by means of which it

may be rotated in either direction. Mounted upon the shaft by means of a feather or the like n so as to be capable of sliding along the shaft there is provided a friction wheel n^1 with a driving face of leather or like material adapted to contact with and drive the friction disk d^1 . The bearings a^4 are provided to be capable of adjustment for the purpose of regulating the pressure between the driving friction wheel n^1 and the disk d^1 . An arm n^2 is pivoted to a pedestal n^3 and carries means for engaging a groove provided in the boss of the friction wheel n^1 , so that by movement of the arm, the friction wheel may be shifted to any position on the radius of the friction disk according to the speed it is desired to transmit.

In order to provide means for retaining the friction wheel at any particular position a quadrant or guide n^4 for the arm n^2 is provided having a series of holes in its upper face into which a pin provided upon the arm, or provided to pass through a hole therein, may engage and so retain the arm and the friction wheel in position.

It will be understood that the invention is not limited to the use of the variable speed gear described, as this may be of any suitable kind and if necessary a gear giving an automatic variation of speed or change in direction of rotation may be employed.

What I do claim as my invention and desire to secure by Letters Patent is:—

1. An electro-depositing apparatus comprising a vat, an electrolyte, a supporting frame, a rotatable hollow spindle, a cathode carrier supported by said spindle, an earthenware pedestal in said vat, an anode carrier mounted on said pedestal, a tube passing through said spindle and connected to the anode carrier, a contact ring mounted on said tube and insulated therefrom, means for securing electrical communication between said contact ring and the cathode carrier, means for conducting an electric current to the contact ring and the anode carrier, cathode and anode holders respectively suspended from the cathode and anode carriers, cathodes and anodes, and means for rotating the hollow spindle.

2. An electro-depositing apparatus comprising a vat, an electrolyte, a supporting frame, a rotatable hollow spindle, a cathode carrier supported by said spindle, an earthenware pedestal in said vat, an anode carrier mounted on said pedestal, a tube passing through said spindle and connected to the anode carrier, a contact ring mounted on said tube and insulated therefrom, means for securing electrical communication between said contact ring and the cathode carrier, said means comprising a vertically disposed spindle, brushes on said spindle, said brushes contacting with the contact ring and the cathode carrier, means for conduct-

ing an electric current to the contact ring and the anode carrier, cathode and anode holders respectively suspended from the cathode and anode carriers, cathodes and 5 anodes, and means for rotating the hollow spindle.

3. An electro-depositing apparatus comprising a vat, an electrolyte, a supporting frame, a rotatable hollow spindle mounted in 10 said frame, a cathode carrier supported by said spindle, an earthenware pedestal in said vat, an anode carrier mounted on said pedestal, a tube passing through said spindle and connected to the anode carrier, a contact ring 15 mounted on said tube and insulated therefrom, means for forming electrical communication between said contact ring and the cathode carrier, means of conducting an electric current to the contact ring and the 20 anode carrier, ridges on the cathode and anode carriers, cathode and anode holders respectively suspended from the cathode and anode carriers and contacting with the ridges, cathodes and anodes, and means for 25 rotating the hollow spindle.

4. An electro-depositing apparatus comprising a vat, an electrolyte, a supporting frame, a rotatable hollow spindle mounted in said frame, a cathode carrier supported 30 by said spindle, an earthenware pedestal in said vat, an anode carrier mounted on said pedestal, a tube passing through said spindle and connected to the anode carrier, a contact ring mounted on said tube and 35 insulated therefrom, means for forming electrical communication between said contact ring and the cathode carrier, said means comprising a vertically disposed spindle, brushes on said spindle, said 40 brushes contacting with the contact ring and the cathode carrier, means of conducting an electric current to the contact ring and the anode carrier, ridges on the cathode and anode carriers, cathode and anode hold- 45 ers respectively suspended from the cathode and anode carriers and contacting with the ridges, cathodes and anodes, and means for rotating the hollow spindle.

5. An electro-depositing apparatus comprising a vat, an electrolyte, a supporting frame, a rotatable hollow spindle, a cathode carrier supported by said spindle, an earthenware pedestal in said vat, an anode carrier mounted on said pedestal, a tube 50 passing through said spindle and connected to the anode carrier, a contact ring mounted on said tube and insulated therefrom, means for securing electrical communication between said contact ring and the cathode carrier, means for conducting an electric current to the contact ring and the anode carrier, cathode and anode holders 55 respectively suspended from the cathode and anode carriers, cathodes and anodes, and 60 means for rotating the hollow spindle, and 65 means for controlling the speed of rotation of the cathode carrier.

6. An electro-depositing apparatus comprising a vat, an electrolyte, a supporting frame, a rotatable hollow spindle mounted in said frame, a cathode carrier supported by said spindle, an earthenware pedestal in said vat, an anode carrier mounted on said pedestal, a tube passing through said spindle and connected to the anode carrier, 70 a contact ring mounted on said tube and insulated therefrom, means for forming electrical communication between said contact ring and the cathode carrier, means of conducting an electric current to the contact ring and the anode carrier, ridges on the cathode and anode carriers, cathode and anode holders respectively suspended from the cathode and anode carriers and contacting with the ridges, cathodes and anodes, 75 and means for rotating the hollow spindle, and means for controlling the speed of rotation of the cathode carrier.

7. An electro-depositing apparatus comprising a vat, an electrolyte, a supporting frame, a rotatable cathode carrier, a stationary anode carrier, ridges on said carriers, cathode and anode plate holders suspended from the cathode and anode carriers and contacting with the ridges, each of said 90 holders comprising a plate having a curved upper end in which inclined surfaces are formed, said inclined surfaces being adapted to contact with the ridges, contact surfaces, means of securing the holder to the cathode 95 carrier, means of securing the cathode to the holder, and a handle portion at the upper end of said holder, cathodes and anodes, and means for rotating the cathode carrier.

8. An electro-depositing apparatus comprising a vat, an electrolyte, a supporting frame, a rotatable hollow spindle, a cathode carrier supported by said spindle, an earthenware pedestal in said vat, an anode carrier mounted on said pedestal, a tube passing through said spindle and connected to the anode carrier, a contact ring mounted on said tube and insulated therefrom, means for securing electrical communication between said contact ring and the cathode carrier, 105 each of said holders comprising a plate having a curved upper end, contact surfaces, means of securing the holder to the cathode carrier, means of securing the cathode to the holder, and a handle portion at the upper 110 end of said holder, means for conducting an electric current to the contact ring and the anode carrier, cathode and anode holders respectively suspended from the cathode and anode carriers, cathodes and anodes, and 115 means for rotating the hollow spindle.

9. An electro-depositing apparatus comprising a vat, an electrolyte, a supporting frame, a rotatable hollow spindle mounted in said frame, a cathode carrier supported 120

by said spindle, an earthenware pedestal in said vat, an anode carrier mounted on said pedestal, a tube passing through said spindle and connected to the anode carrier, a contact ring mounted on said tube and insulated therefrom, means for forming electrical communication between said contact ring and the cathode carrier, means of conducting an electric current to the contact ring and the anode carrier, ridges on the cathode and anode carriers, cathode and anode holders respectively suspended from the cathode and anode carriers and contacting with the ridges, each of said holders comprising a plate having a curved upper end in which inclined surfaces are formed, said inclined surfaces being adapted to contact with the ridges, contact surfaces, means of securing the holder to the cathode carrier, means of securing the cathode to the holder, and a handle portion at the upper end of said holder, cathodes and anodes, and means for rotating the hollow spindle.

10. An electro-depositing apparatus comprising a vat, an electrolyte, a supporting frame, a rotatable hollow spindle mounted in said frame, a cathode carrier supported by said spindle, a stationary anode carrier, a tube passing through said spindle and connected to the anode carrier, a contact ring mounted on said tube and insulated therefrom, means for forming electrical communication between said contact ring and the cathode carrier, means of conducting an electric current to the contact ring and the anode carrier, ridges on the cathode and anode carriers, cathode and anode holders respectively suspended from the cathode and anode carriers and contacting with the ridges, cathodes and anodes, and means for rotating the hollow spindle.

15. An electro-depositing apparatus comprising a vat, an electrolyte, a supporting frame, a rotatable hollow spindle mounted in said frame, a cathode carrier supported by said spindle, a stationary anode carrier, a tube passing through said spindle and connected to the anode carrier, a contact ring mounted on said tube and insulated therefrom, means for forming electrical communication between said contact ring and the cathode carrier, means of conducting an electric current to the contact ring and the anode carrier, ridges on the cathode and anode carriers, cathode and anode holders respectively suspended from the cathode and anode carriers and contacting with the ridges, cathodes and anodes, and means for rotating the hollow spindle.

20. An electro-depositing apparatus comprising a vat, an electrolyte, a supporting frame, a rotatable hollow spindle mounted in said frame, a cathode carrier supported by said spindle, a stationary anode carrier, a tube passing through said spindle and connected to the anode carrier, a contact ring mounted on said tube and insulated therefrom, means for forming electrical communication between said contact ring and the cathode carrier, means of conducting an electric current to the contact ring and the anode carrier, ridges on the cathode and anode carriers, cathode and anode holders respectively suspended from the cathode and anode carriers and contacting with the ridges, cathodes and anodes, and means for rotating the hollow spindle.

25. An electro-depositing apparatus comprising a vat, an electrolyte, a supporting frame, a rotatable hollow spindle mounted in said frame, a cathode carrier supported by said spindle, a stationary anode carrier, a tube passing through said spindle and connected to the anode carrier, a contact ring mounted on said tube and insulated therefrom, means for forming electrical communication between said contact ring and the cathode carrier, means of conducting an electric current to the contact ring and the anode carrier, ridges on the cathode and anode carriers, cathode and anode holders respectively suspended from the cathode and anode carriers and contacting with the ridges, cathodes and anodes, and means for rotating the hollow spindle.

30. An electro-depositing apparatus comprising a vat, an electrolyte, a supporting frame, a rotatable hollow spindle mounted in said frame, a cathode carrier supported by said spindle, a stationary anode carrier, a tube passing through said spindle and connected to the anode carrier, a contact ring mounted on said tube and insulated therefrom, means for forming electrical communication between said contact ring and the cathode carrier, means of conducting an electric current to the contact ring and the anode carrier, ridges on the cathode and anode carriers, cathode and anode holders respectively suspended from the cathode and anode carriers and contacting with the ridges, cathodes and anodes, and means for rotating the hollow spindle.

electric current to the contact ring and the anode carrier and means for rotating the hollow spindle.

11. An electro-depositing apparatus comprising a vat, an electrolyte, a supporting frame, a rotatable hollow spindle mounted in said frame, a cathode carrier supported by said spindle, a stationary carrier, a tube passing through said spindle and connected to the anode carrier, a contact ring mounted on said tube and insulated therefrom, means for forming electrical communication between said contact ring and the cathode carrier, means of conducting an electric current to the contact ring and the anode carrier, ridges on the cathode and anode carriers, cathode and anode holders respectively suspended from the cathode and anode carriers and contacting with the ridges, cathodes and anodes, and means for rotating the hollow spindle.

12. The combination with electro-depositing apparatus of a holder comprising a plate having a curved upper end, inclined contact surfaces, and a handle portion at the upper end of said holder.

In testimony whereof I have hereunto signed my name to this specification in the presence of two subscribing witnesses.

JAMES ALBERT COREY.
